A. A. BENSON AND H. BARNES,
TEMPERATURE INDICATOR FOR RADIATORS.
APPLICATION FILED NOV. 1, 1919.

1,398,218.

Patented Nov. 22, 1921.

Inventors:

ARY A. BENSON
By their Attorney, HORACE BARNES.

DIRECT AND MESNE ASSIGNMENTS, TO AUTO RADIO METER COMPANY, OF
SEATTLE, WASHINGTON, A CORPORATION OF WASHINGTON.

TEMPERATURE-INDICATOR FOR RADIATORS.

1,398,218.

Specification of Letters Patent. Patented Nov. 22, 1921.

Application filed November 1, 1919. Serial No. 335,204.

To all whom it may concern:

Be it known that we, ARY A. BENSON and HORACE BARNES, citizens of the United States, residing at Seattle, in the county of King and State of Washington, have invented certain new and useful Improvements in Temperature-Indicators for Radiators, of which the following is a specification.

This invention relates to improvements in instruments to indicate the temperature of the cooling water in the radiator of an automobile and has for its object the provision of a simple and efficient means to indicate the rise in temperature of the cooling water of a radiator when the same exceeds a predetermined temperature and to make the same visible from the driver's seat of the car.

A further object of the invention is the provision of reflecting apparatus whereby light rays impinging upon the front of the instrument are deflected through the indicator, whereby the instrument may be read from the driver's seat at night.

The invention consists in the novel construction of a temperature-indicating apparatus and the combination and adaptation therewith of light-reflecting devices, as will be fully described in the following specification, illustrated in the accompanying drawings and finally set forth in the appended claims.

In said drawings, Figure 1 is a view in vertical section of apparatus embodying our invention on line 1—1 of Fig. 2. Fig. 2 is a vertical sectional view on line 2—2 of Fig. 3; and Fig. 3 is a view in front elevation. Fig. 4 is a rear view in elevation of the invention.

Referring to said views, the reference numeral 1 indicates the filling tube of an automobile radiator, and 2 the removable cap closure, therefor. Said cap may be formed with a centrally positioned opening provided with an internally threaded ring 3. 5 indicates a circular casing having two substantially flat front and rear opposing faces 6 and 7, respectively, and inclosing a substantially circular chamber 8. Said casing is formed with a throat 10 in its lower portion, to which a tube 11 is integrally or otherwise connected.

Said tube is adapted to be inserted within said filling tube and is connected to said ring 3. The tube is closed at its lower end and 55 is arranged to support a thermostatic member comprising a rod 12 that is connected with a thermostat 13 which is formed of a plurality of inter-connected U-shaped elements and is readily affected by heat to expand it longitudinally. The lower end of the thermostat 13 is supported by a set screw 16 that is screwed through the bottom end of the tube 11 and serves as a means of adjusting the thermostat. 60

17 and 18 indicate, respectively, indicating shutter members that are pivotally mounted adjacent their lower ends upon a pin 20 secured in the side walls 6 and 7 of the casing. Said shutters are disposed upon 65 said pin in side by side relation and are each formed with a downwardly extending oppositely curved projection 17' and 18', respectively, which are arranged to be engaged by the upper extremity of the rod 12 which 70 is beveled, as at 21, and as the thermostat extends in length through the increase of heat in the radiator, the said projections 17' and 18' will be forced apart by the upward movement of the rod 12 and the shutter 80 members will be caused to close from their inoperative positions indicated in full lines in Fig. 1, more or less, toward each other to their opposite extreme or closed positions indicated by broken lines in the same view. 85

Said shutter members are maintained yieldingly in their open condition by means of coil-springs 22 and 23, respectively coiled about the pin 20 and having one end of each engaging the respective shutter, as will be 90 clearly understood. Said shutter members are preferably composed of a transparent material, such as celluloid, and of a contrasting color, such as red, whereby they will be 95 clearly distinguished from the driver's seat when visible.

A glass window 25 of circular configuration is mounted centrally in the rear wall 7 of the casing and the portion of said wall not to cut away to provide for said window 100 is intended to shield the view of said shutters from the driver's seat when the shutters are in their inoperative condition. In the front wall 6 of the casing, we provide a lens 26

formed with a plurality of circular concentric prisms 27 whereby light rays impinging upon them will be straightened out and deflected as much as may be in parallel 5 lines through the window 25, and when the shutter members 17 and 18 are visible through said window, the light will be directed through them. In addition to the lens 26, we provide a concave reflector 28 of 10 circular configuration about said lens and extending forwardly of the lens, whereby light rays caught by said reflector will be reflected onto said lens and thence through onto the shutters when in view.

15 It may be stated that the concentric prism rings 27 upon the lens 26 serve an additional and useful purpose, inasmuch as they serve as graduation marks to indicate to the driver the approximate degree of heat within the 20 radiator, as said rings are clearly visible through the window 25 at all times even when the shutters 17 and 18 are closed.

The manner of operation of our invention is believed to be apparent from the foregoing description. It may be stated, however, that the thermostat is extremely sensitive to changes in temperature and will act 25 immediately and positively upon the shutters to actuate them into visible positions, 30 the relative lengths of the projections 17' and 18' being such that considerable movement of the shutters is effected by a relatively slight movement of the rod. The rod is also capable of adjustment in its engagement 35 with said projections by means of the adjustment screw 16.

When installed in operative position upon the radiator of an automobile, the rear side 7 of the instrument will be viewed by the 40 driver and as long as no undue amount of heat is generated in the radiator, the shutters will be invisible through the window 25 but upon an increase of temperature to a predetermined degree to which 45 the thermostat will be set through the adjustment screw 16, the projections 17' and 18' will be engaged to actuate the shutters more or less across the opening closed by said window and due to the color of said 50 shutters will be plainly seen when their edges first appear.

The circular prisms 27 of the lens 26 will also be evident and thereby the degree of temperature of the radiator may be more 55 easily determined.

At night it is evident that light rays from whatever source, such as from headlights on approaching vehicles or street lamps, that impinge on said lens 26 or upon 60 the reflector 28, will be directed through the lens and through the transparent shutters 17 and 18 and will cause the latter to be clearly seen at night to almost the same degree as by day.

65 Having described our invention, what we

claim as new and desire to secure by Letters-Patent is—

1. In an instrument of the class described, a casing provided with a sight opening in its rear wall and a lens in its front wall, 70 a pair of shutters pivotally mounted to vibrate across said opening, and a thermostatic member arranged to impinge upon said shutters to close said shutters across said opening upon an increase of temperature 75 affecting said thermostatic member.

2. An instrument of the class described, consisting in a casing having a window in its rear wall, and a lens in its front wall adapted to direct the light rays impinging thereon toward said window, and a pair of thermostatically arranged shutters pivotally mounted in said casing arranged to be moved across said window. 80

3. In an instrument of the class described, 85 a casing having a window in its rear wall, and a lens in its front wall adapted to receive light rays and direct them toward said window, a shutter arranged to vibrate across said window, and thermostatic means 90 to cause said shutter to move across said window in response to predetermined variations in temperature.

4. In an instrument of the class described, 95 a casing having a window in its rear wall and a lens in its front wall, of a movable shutter arranged to move across said window, and a thermostatic device for actuating said shutter in response to changes of temperature. 100

5. An instrument of the class described, 105 consisting in a casing, light openings in the front and rear walls of the casing, a shutter pivotally mounted in said casing and formed of translucent material to admit the passage of light therethrough from the front light opening, and a thermostatic device for actuating said shutter across said light openings in response to changes of 110 temperature. 110

6. An instrument of the class described, 115 consisting in a casing having a window in its rear wall, and a lens in its front wall, said lens being formed with a plurality of concentric prisms adapted to direct the light rays impinging thereon toward said window, a circular reflector upon said front wall arranged to reflect light rays impinging thereon toward said lens, a pair of transparent shutters pivotally mounted in 120 said casing, of a contrasting color, said shutters normally remaining concealed from view through said window, and a thermostatic device for actuating said shutters across said window in response to changes 125 of temperature.

7. An instrument of the class described, 130 consisting in a casing having a window in its rear wall and a lens in its front wall, said lens being formed with a plurality of

concentric prisms adapted to direct light rays toward said window, a circular reflector upon said front wall arranged to reflect light rays impinging thereon toward 5 said lens, a pair of shutters pivotally mounted in said casing, said shutters normally remaining concealed from view through said window, springs arranged to maintain said shutters yieldingly in their concealed 10 positions, said shutters each having a downwardly directed projection, a tube depending from said casing, and a thermostatic column secured within said tube and engaging said projection at its upper end to actuate 15 said shutters in accordance with variations of temperature affecting the rod.

8. An instrument of the class described, consisting in a casing having a window in its rear wall, and a lens in its front wall, 20 said lens being formed with a plurality of concentric prisms adapted to direct the light rays impinging thereon toward said window, a circular reflector upon said front

wall arranged to reflect light rays impinging thereon toward said lens, a pair of 25 transparent shutters pivotally mounted in said casing of a contrasting color, said shutters normally remaining concealed from view through said window, springs arranged to maintain said shutters yieldingly 30 in their concealed positions, said shutters having downwardly directed projections, a rod having a wedge-shaped upper end arranged to engage between said projections and move said shutter members, a thermostatic member secured to the bottom end of said rod and arranged to move said rod in response to variations of temperature affecting it, a tube depending from said casing and arranged to inclose said rod and 35 said thermostat, and a screw adjustably supporting the bottom end of said thermostat.

Seattle, Washington, October 20th, 1919.

ARY A. BENSON.
HORACE BARNES.
